UNITED STATES PATENT OFFICE.

PHILIP HIRSHFIELD, OF LOWELL, MASSACHUSETTS.

BUTTON.

SPECIFICATION forming part of Letters Patent No. 311,758, dated February 3, 1885.

Application filed May 21, 1884. (No model.)

To all whom it may concern:

Be it known that I, PHILIP HIRSHFIELD, a citizen of the United States, residing at Lowell, in the county of Middlesex and Commonwealth of Massachusetts, have invented certain new and useful Improvements in Buttons, of which the following is a specification.

My invention relates to buttons; and it consists in protectors for protecting the button-thread and the button-holes from wearing each other, said protector having the end intended to be next the button slotted, as hereinafter specified.

In the accompanying drawings, Figure 1 is an isometric view of a covered button with my improvement used in connection therewith; Fig. 2, a side elevation of such a button, with a protector in central section; Fig. 3, a plan of the protector detached.

20 In the drawings, the button A (shown in Figs. 1 and 2) is a cloth-covered button, of the usual construction, and having a soft shank, b, through which a needle and thread can be passed to secure the button to a garment.

25 It is customary, in sewing on all such buttons as are shown in the drawings, to wind the thread several times around the parts of the thread which connect the button to the cloth before fastening the end of the thread in the cloth. This is done partly to set the button out from the cloth by a shank of thread, and thereby make it easier to engage the button and the button-hole with each other and allow the edges of the button-hole to pass between the button and the cloth to which the button is attached, and partly to protect the connecting-threads from being worn off by the edges of the button; but the winding-threads soon become worn and broken, and leave the connecting-threads unprotected, and the latter threads rapidly wear the edges of the button-hole.

To save the connecting-threads and the edges of the button-hole, I use a protector, which may be of the form, C, shown in Figs. 1, 2, and

3, the same being a short tube circular in 45 cross-section and flaring at the ends, but preferably of larger diameter at the outer end or end next the button A, and provided at said outer end with slots c, through which the needle and thread may be passed when used with 50 buttons which are not adapted to be sewed through and through. The slots c allow the needle and thread to be passed through the cloth or garment up into the central opening, c', of the protector, through the soft shank of 55 such a button as is shown in Fig. 2, and out at one of the slots, and then back through the slot, shank, and central opening and cloth.

When the protector is used, the connecting-threads are not wound and the button-thread 60 is wholly on the inside of the protector.

I am aware that buttons perforated near the center have been provided with a hollow tubular shank, and that buttons having hollow shanks, slotted near their inner ends to 65 receive a staple or wire fastening, have been made, and I claim neither of these constructions; but I believe it to be new to use between a button provided with a shank and the article to which such button is to be attached 70 to a tubular protector surrounding said shank, and having in its outer edge slots to enable a needle and thread to be passed through such shank.

I claim as my invention—

The protector consisting of a tube having flaring open ends, and adapted to be placed between a button and the article to which such button is to be sewed, and to surround and protect the threads which connect said button 80 to said article, said protector having the end intended to be next the button slotted, as herein described, as and for the purpose specified.

PHILIP HIRSHFIELD.
